WRINGER MECHANISM

Carl Moon, Detroit, Mich.

Application March 8, 1935, Serial No. 9,927

2 Claims.

(Cl. 68—32)

This invention relates to roll wringer mechanism, more particularly to means for releasing pressure between wringer rolls, and has for its principal object provision of mechanism for accomplishing such release by means of movement of the wringer frame with respect to its supporting post.

Another object is to provide a wringer frame pivotally mounted upon a post structure and mechanism co-operative between the post and wringer whereby pivotal movement of the wringer brings about release of the roll pressure mechanism.

An additional object lies in the provision of a wringer frame pivotally mounted upon a post structure, operable upon pivotal movement to release pressure between the wringer rolls, the same having in combination a co-operative mechanism adapted to assist said pivotal movement.

Another object is to provide a wringer roll mechanism pivotally mounted upon a post structure, operable upon pivotal movement to release pressure between the wringer rolls, the same having in combination a co-operative manually operative mechanism adapted to bring about said pivotal movement.

A further object is to provide a simple and inexpensive mechanism for releasing roll pressure in a quick and easy manner.

Other objects will appear in the following description and accompanying drawing in which:

Fig. 1 is a side elevational view of a wringer embodying my invention wherein that portion comprising the invention is shown in section to facilitate description;

Fig. 2 is a fragmental plan view showing details of parts to be described;

Fig. 3 is a view similar to Fig. 2, showing certain parts in operated position as will be described and

Fig. 4 is a fragmental side elevational view showing details of structure with certain parts in operated position to be described.

Fig. 1 discloses my device as combined with a conventional roll wringer mechanism which includes a wringer frame 11 having upstanding end portions 12 and 13, upper and lower rolls 14 and 15, a releasable top frame 16, and a spring 17 supported in the top frame adapted to apply resilient pressure upon the upper roll 14 to force the same downwardly upon lower roll 15 to hold the rolls in pressure relation.

The lower roll has driving connection with a power source, not shown, through a flexible coupling 18, a gear 19 and a gear and clutch mech-

anism operated by a revolving shaft 20. The drive mechanism is thought sufficiently well known to obviate detailed description.

Upright 12 includes a bracket portion 21 having extending upper and lower portions 22 which are pivotally supported on the wringer post structure 23 by means of screws 24 whereby the wringer frame may be pivotally moved upon the post as indicated in Fig. 3. The flexible coupling 18 permits such movement without alteration of the roll drive connection.

Secured to the upper side of the wringer post is a bracket member 25 which has an extending portion 26, best shown in Fig. 4, and upon the end of this is secured an upstanding lug 27.

Lug 27 is movably received in a recessed portion of a member 28, which is pivotally mounted at 29 upon end member 12.

Member 28 has outwardly extending portions 30 for a purpose to be described shortly.

Referring to the top frame 16, it will be noted that at its right hand end, Fig. 1, it is releasably attached to upright 13 by means of a conventional hook arrangement 31, and at its left hand end by means of a latch member 32 engaged in an opening 33 in the top frame.

Latch 32 is movably disposed inside of upright 12 by means of a resilient support member 34 secured at 35 to upright 12. The support member has an opening 36 of sufficient proportions to clear the pivotal mechanism of member 28 and member 34 is thus adapted to lie adjacent the wall of upright 12, as shown in Fig. 1, with hook 32 engaged in opening 33 of the top frame.

With parts in this position the top frame is obviously retained upon uprights 12 and 13 in position to render spring 17 effective to hold the rolls in pressure relation. The relative position of parts 26, 28 and 34 is clearly shown in Fig. 2.

Fig. 3 illustrates relative movements of the several parts when the wringer frame is moved upon its pivotal bearings 24—24, wherein the lug 27 remains stationary while the pivotal support 29 of member 28 moves with the wringer frame and thus brings about rotation of member 28 whereby one of the portions 30 engage and move the latch support member 34 backwardly to withdraw latch 32 from opening 33 whereupon the top frame is released from upright 13. When released, the top frame moves upwardly, as in Fig. 4, to relax spring 17 and remove pressure between the rolls.

Fig. 2 will illustrate that when the wringer rests in suitable alignment with its support, the two side portions of member 34 are adapted to lie

evenly against the two projections 30 of the member 28.

It will be obvious that the pressure of member 34 applied in this manner is adapted to hold member 28 in alignment and that the recess of member 28, engaging lug 27 provides a means for holding the wringer in suitable alignment with its support.

Movement of the wringer frame in a direction 10 opposite that shown in Fig. 3 will obviously operate member 28 in an opposite manner to bring about the same result.

The foregoing has described a release mechanism similar to that shown in my co-pending 15 application No. 751,809.

The following will describe a co-operative mechanism adapted to be used in combination with that just described, to increase the utility thereof.

20 Upon the post structure 23 is a stud 40 upon which is pivotally mounted a member 41 having arm portions 42 extending outwardly upon both sides of the wringer rolls.

Member 41 has a central extending portion 43 having a downwardly directed stud 44 engaging in an extension of a recess 45 the latter being that also engaging lug 27.

Operation of member 28 to release the wringer rolls has already been described. It is thought 30 obvious that arm portions 42, lying alongside the wringer rolls as shown in Fig. 2, are in position convenient for manipulation by an operator, and that manipulation into the position shown in Fig. 3 will operate member 28, with stud 27 as a fulcrum, to move the wringer out of its normal alignment whereby release of the roll tensioning mechanism is accomplished.

In connection with this invention it is to be 40 particularly noted that movement of the wringer to release the rolls may, and would usually be, brought about through movements which are instinctive on the part of an operator.

During practical use should an operator's fingers be caught between the rolls, initial instinctive movement would be to pull away and this movement would obviously cause the pivotal movement described to release the roll pressure.

There is a further manual movement which 50 may be instinctive on the part of many operators when an accident occurs, and this must be considered in connection with safety release mechanisms.

For example, if an operator's fingers become 55 caught in the rolls, the first instinctive movement would perhaps be to pull away as above noted, however, it may be that simultaneously or very soon after the initial pull the operator would place the other hand on some part of the mechanism to push the body away, or to assist

in resisting the feed-in movement of the engaged fingers.

It will be noted that arms 42 are placed in position to be most convenient when the operator makes a more or less involuntary movement to 5 push against something with the free hand as above stated.

Obviously the instinctive movements of an operator positioned at the top side in Fig. 3 would include pulling the engaged hand to swing the 10 wringer into releasing position as shown, and pushing against arm 42, toward the position shown to indirectly bring about an identical releasing action.

It is thought apparent that pulling the wringer 15 mechanism or pushing arm 42 will bring about release of the wringer. Either mechanism operated separately will bring about the same result and when both mechanisms are operated simultaneously they co-operate to bring about a like 20 result.

Modifications of the structure and functions herein described are obviously possible without alteration of the principle disclosed. I do not wish 25 to be limited in structure or principle except within the scope of the appended claims.

What I claim is:

1. In a wringer organization, the combination of a support structure, a wringer frame mounted thereon for pivotal movement in a horizontal 30 plane, wringer rolls, pressure mechanism for the rolls, a safety release device releasing pressure on the rolls, mechanism operating the release device to release pressure on the rolls, said release operating mechanism being actuated by means of said pivotal movement of the wringer frame, means to bring about said pivotal movement comprising a release handle mounted on said support structure, the handle extending across the front of the wringer and having connection with said wringer frame whereby manual movement of the handle causes pivotal movement of the wringer frame.

2. In a wringer mechanism the combination of a support structure, a wringer frame mounted 45 for pivotal movement thereon, wringer rolls in the frame, pressure mechanism for the rolls, latching mechanism holding said pressure mechanism in active position, a member actuated by means of said pivotal movement of the wringer frame actuating said latch to release pressure on the rolls, a release handle mounted on said support structure and extending across the front of the wringer, having connection with said wringer frame whereby manual movement of said 50 arm causes pivotal movement of the wringer frame.

CARL MOON.
